UNITED STATES PATENT OFFICE.

MAX HENIUS, OF CHICAGO, ILLINOIS.

DESIGN FOR A BOTTLE.

SPECIFICATION forming part of Design No. 31,126, dated July 4, 1899.

Application filed May 31, 1899. Serial No. 718,919. Term of patent 14 years.

To all whom it may concern:

Be it known that I, MAX HENIUS, a citizen of the United States, residing at Chicago, in the county of Cook and State of Illinois, have 5 invented and produced a new and original Design for a Bottle, of which the following is a specification.

The accompanying drawing shows my design of a bottle by a perspective view.

10 As shown in the accompanying drawing, the leading feature of my design consists in the square shape in cross-section of the body A of the bottle, having on each of its four sides a similar countersunk flat-based panel 15 B, formed with straight beveled sides *a a*, connected by beveled arch-shaped ends *b b*.

The neck C of the bottle is slender in proportion to the body A and, as shown, is about two-thirds the length thereof.

The color of the glass bottle which is preferred is milk-white.

Having described my invention, what I claim as new, and desire to secure by Letters Patent, is—

The design for a bottle, as herein shown 25 and described.

MAX HENIUS.

In presence of—

M. J. FROST,
R. T. SPENCER.
